UNITED STATES PATENT OFFICE.

EMIL A. DENZ, OF CHICAGO, ILLINOIS.

POTATO-CHIP-FRYING MACHINE.

Application filed December 3, 1923. Serial No. 678,356.

To all whom it may concern:

Be it known that I, EMIL A. DENZ, a citizen of the United States, residing at Chicago, in the county of Cook and State of Illinois, have invented certain new and useful Improvements in Potato-Chip-Frying Machines, of which the following is a specification.

The objects of this invention are to provide a machine that will slice and fry potato-chips in a continuous process; to provide such a machine to have a large output; to increase the efficiency of the heating apparatus generally used for such purposes; to simplify the arrangement of the operating parts; to provide an improved impeller of greater driving force and which will splash less grease; to provide an elevator which may be conveniently lifted out of the cooking-oil for cleaning; and other objects which will appear in the following description.

The preferred form of my invention is illustrated in the accompanying drawings in which:

Fig. 1 is a general plan view; and

Fig. 2 is a side elevation.

The body of the machine comprises a tank 3 of sheet metal construction and supported by legs 4. A bottom or horizontal partition 5 is spaced intermediate the upper and lower edges of the tank 3, forming an inverted heating chamber 6 underneath the bottom. A series of gas burner pipes 7 extend longitudinally throughout the heating chamber, near to the bottom 5. The heating chamber 6 has inlet and cleaning ports 8 spaced around the side walls.

The exhaust pipe 9 runs through the upper middle part of the heating chamber 6, and has inlets 10 along its length. Fuel gas is supplied to the burner pipes from the header 11.

The compartment 12, above the bottom 5, is partitioned off by vertical walls into a continuous tortuous channel 13, which is filled up to about the level of the dotted line 14 with the cooking-oil. The cooking-oil is heated by the flame from the burners 7 and is caused to circulate by the revolving propeller 15 which is rotatably mounted to dip into the stream of fluid and drive the fluid along the channel 13, passing under the hopper 16, and around the channel to the end 55 of the conveyor 17, and on to the impeller 15.

A motor 18 is mounted on a shelf 20 which

extends outward from the frame 21. The frame 21 is formed by two angle bars 22 and is attached to one end of the tank 3. The motor is geared to the drive shaft 23, which is mounted in the brackets 24 secured to the angle bars 22, and the extending portion of the shaft 23 is journaled in the bearings 25 in the frame member 26, which is secured to the top of the tank 3 at the opposite side 65 from the conveyor 17. The motor pinion 27 meshes with the gear 28 which is mounted on the shaft 29 which is carried by the frame 21; the shaft 29 carries the pinion 30 which meshes with the drive shaft gear 31. The upper elevator or conveyor shaft 32 is also mounted in the frame 21 and is driven from the shaft 23 through the pinion 33 on the shaft 23, and the gear 34 on the shaft 32.

The impeller 17 comprises a sheet metal frame 35 which is pivoted at its upper end to the shaft 32, and the lower end rests on the bottom of the channel 13. The lower end of 35 carries a roller 36, and the conveyor belt 37 passes around the bottom roller 36 80 and around the top roller 38 which is on the shaft 32.

The impeller 15 is driven from the shaft 23 through the bevel pinion 39, on the shaft 23, and the bevel gear 40 which is keyed on the shaft 41 which is mounted in the bracket 42. The bracket 42 is removably secured on the top of the tank 3. The impeller shaft 44 is driven from the shaft 41 through the chain connection 43. The impeller 15 is built up of disk shaped side plates 45 connected by narrow peripheral vanes 46 which are set to curve forwardly.

The hopper 16 is circular and is removably secured on the top of the tank 3. The hopper 16 has a sloping bottom 47 which converges into the bottom opening 48, located directly over the channel 13. The cutter or slicer disk 49 is mounted for horizontal rotation directly below the opening 48, and 49 has its bearings in the frame member 26. The cutter disk 49 is driven by a gear connection from the shaft 50, which, in turn, is geared to the drive shaft 23 through the gears 51 and 52.

The cutter disk carries two or more slicer knives 53, which have their edges set radially to the axis of the disk 49. Cutter bars 54 are provided, across the bottom opening 48, which lie at a tangential angle to the 110 spindle of the disk 49, to form a shearing angle with the knife edges of 53.

The arrangement just described permits of a symmetrical construction of the cutter disk 49 because the knives 53 are oppositely disposed and therefore balance each other.

- 5 The pared potatoes are dumped into the hopper 16 which is of sufficient capacity to supply the machine for a long period of time. The plurality of cutting bars 54 furnishes several edges against which the 10 knives 53 operate to slice the potatoes. In the usual type of slicer the cutting knife operates against only one stationary edge. Such slicers are designed to operate on an integral piece of material; while with pieces 15 of small weight, a single blade cutter has to operate at a high rate of speed to shear off whole slices, especially when there are not many potatoes in the hopper to weight the bottom layer. Therefore the cutter 49 having 20 a plurality of knives 53 operating against a plurality of bars 54, cuts off larger slices and may operate at a lower rate.

The timing relation between the cutter action and the flow of the stream in the 25 channel 13, is such that a layer of slices is deposited evenly over the surface of the liquid and just has sufficient time to flow out of the way of the next layer sliced off by the succeeding knife. This greatly increases 30 the output of the machine.

The hopper 16 is readily removed from the tank leaving the cutter disk 49 accessible for cleaning.

The impeller 15 is of a stable construction 35 and drives the stream with considerable force without the usual amount of splashing. The blades 46 do not extend all the way to the center of the impeller, so that, when the blades lift out of the liquid, the liquid flows 40 off from the inner edge of the blades and is not carried over the top of the impeller.

As the conveyor belt is travelling over the rollers, it is dipped into the hot grease and then cooled in the atmosphere and a heavy 45 coating quickly forms which collects dust and dirt, necessitating frequent cleaning. By having the conveyor frame pivoted on the upper shaft 32, the lower end of the conveyor may be lifted out and thrown back 50 to remove the belt or the belt can be easily cleaned in place.

The heating chamber 6, as described, is closed above and has walls extending downwardly around the sides to retain the heat 55 under the tank bottom 5. Consequently, without some means being provided for removing, the burnt gases are trapped in the chamber 6. Soot forms rapidly and even clogs up the burner holes so that a bar must 60 be passed through the holes 8 and the soot rubbed from the burner pipes 7. By supplying the ventilating duct or exhaust pipe 9 I draw the burnt gases off from the middle part of the heating chamber 6 and allow 65 fresh air to flow into the chamber to supply

the combustion. This also increases the efficiency of the machine by raising the temperature of the cooking-oil.

Claims:

1. In a potato-chip frying machine; a 70 tank having a horizontal partition wall or bottom located intermediate the top and bottom edges of the said tank, forming a cooking-oil receptacle above and an inverted heating chamber below the said bottom; a 75 series of longitudinally extending gas burner pipes in the upper part of the heating chamber; inlet ports along the side walls of the heating chamber; and a perforated exhaust pipe extending longitudinally 80 through the upper middle part of the heating chamber.

2. In a potato chip frying machine, a 85 rectangular tank having a horizontal bottom partition spaced intermediate the upper and lower edges thereof forming a cooking compartment above and a heating compartment below the partition, a series of gas burners distributed underneath the bottom, and an exhaust flue having openings along its length and extending longitudinally underneath the middle portion of the bottom partition.

3. In a potato chip frying machine, a 90 tank divided into a continuous tortuous channel, an elevator drive shaft mounted above the top of the tank, an elevator frame pivoted on the said shaft and having an end resting on the bottom of the channel, a roller rotatably mounted in the lower end of the frame, and an endless elevator belt 100 passing over the shaft and the roller.

4. In combination in a potato chip frying machine, a rectangular tank, vertical partitions dividing the tank into a continuous tortuous channel a portion of which extends entirely across one end of the tank, a drive shaft extending across the said end and above the top of the tank, a continuous belt elevator located at one side of the said end and which slopes down into the channel and is connected for driving with the said drive shaft, a jack shaft geared to the drive shaft and extending over the top of the tank at the said end and opposite from the elevator, a horizontally mounted slicer having its shaft geared to the said jack shaft, a second jack shaft geared to the drive shaft and extending over the top of the tank at a point between the first mentioned jack shaft and the elevator, an impeller mounted in the channel and having its spindle located below the top of the tank, and a driving connection between the impeller spindle and the second mentioned jack shaft.

5. In combination in a potato chip frying machine, a rectangular tank having a horizontal bottom spaced intermediate the upper and lower edges of the tank, form-

ing a cooking compartment and an inverted heating chamber below the compartment, a frame mounted at one end and at one side of the end of the tank, a drive shaft 5 mounted in the frame and extending across the end and above the top edge of the tank, a jack shaft geared to the drive shaft and extending over the top of the tank, and an impeller mounted in the tank and having its 10 spindle located below the top edge of the tank, and a driving connection from the jack shaft to the impeller spindle.

6. In combination in a potato chip frying machine, a rectangular tank, vertical 15 partitions dividing the tank into a continuous tortuous channel a portion of which extends across one end of the tank, a frame mounted on the outside of the tank at one side of the said end, a drive shaft mounted 20 in the frame above the top of the tank and extending across the end, a jack shaft

geared to the drive shaft and extending over the top of the tank, a slicing mechanism geared to the jack shaft and mounted over the end portion of the channel, a second jack shaft geared to the drive shaft and extending over the top of the tank and positioned between the first mentioned jack shaft and the frame, an impeller mounted in the channel below the second mentioned jack shaft and having its spindle located below the top of the tank, a driving connection from the second mentioned jack shaft to the spindle, a conveyor having its drive shaft mounted in the frame and 35 geared to the main drive shaft mentioned above and having its frame pivoted on the conveyor drive shaft and the lower end of the frame resting on the bottom of the channel, and means mounted on the frame for 40 actuating the main drive shaft.

EMIL A. DENZ.
